No. 13, 022

July 4, 1882

UNITED STATES PATENT OFFICE.

SILVIUS HURSEN, OF VICKSBURG, MICHIGAN.

DESIGN FOR A FAMILY-CHART.

SPECIFICATION forming part of Design No. 13,022, dated July 4, 1882.

Application filed April 5, 1882. Term of patent 14 years.

To all whom it may concern:

Be it known that I, SILVIUS HURSEN, a citizen of the United States, and a resident of Vicksburg, in the county of Kalamazoo and State of Michigan, have invented a new and valuable Improvement in Designs for Family-Charts; and I do hereby declare that the following is a full, clear, and exact description of the construction and operation of the same, reference being had to the annexed drawing, making a part of this specification, and to the letters and figures of reference marked thereon, the figure of the drawing being a representation of my design.

15 This design has relation to memorial registers for use in families; and it consists in the novel configuration or ornamental-work bordering spaces for photographic representations, these spaces being symmetrically arranged, and having in connection therewith horizontal scroll-work suitable for inscribing names, dates, and other items of record, all as hereinafter set forth.

In the accompanying drawing, the letter A 25 designates a central space, B laterally arranged spaces, and C upper and lower spaces, designed to receive photographic illustrations relating to the members of a family, its connections, and residence. Usually the central 30 space is designed for the picture of the residence, the parents' pictures being laterally arranged, the grand-parents' pictures below, and

those of the children above. Bordering these spaces, and defining them, are the representations of pillars or columns *a*, horizontal scroll-work *b*, and ornamental fancy work *c*, blending with said pillars or columns and scroll-work in such a manner as to give unity to the design and produce a pleasing effect.

The horizontal scroll-work is usually provided with ruled lines, in order that inscriptions may be easily placed thereon, said inscriptions referring to the names of the members of the family whose pictures are represented, their ages, the dates of birth, death, or other items of importance relating thereto which require a record.

Having described this design, what I claim and desire to secure is—

The design for family memorial register, 50 consisting of the symmetrically-arranged ornamental-bordered spaces for photographic representations, having in connection therewith horizontal scroll-work suitable for inscribing names, dates, and other items of record, 55 substantially as specified.

In testimony that I claim the above I have hereunto subscribed my name in the presence of two witnesses.

SILVIUS HURSEN.

Witnesses:

ALANSON F. JOSLIN,
DAVID R. CONDEN.
